UNITED STATES PATENT OFFICE

MILFRED L. GREENSTREET, OF ST. LOUIS, MISSOURI

CONVERTIBLE BENCH

Application filed January 20, 1928. Serial No. 248,022.

This invention relates to new and useful improvements in a combined bench and table of the type disclosed in my copending application filed July 28, 1927, Serial No. 208,951 which matured into Patent No. 1,757,960, granted May 13, 1930. In this type of furniture, the back of the bench is so mounted as to enable the adjustment thereof into a horizontal position to serve as a table.

10 The objects of the present invention are to provide simple and effective means for operatively mounting and securing said back to said bench whereby said back may be readily adjusted into either one of its positions.

15 Further objects of the invention are to so construct the bench that the back thereof can be rigidly supported in extended horizontal position without the use of extraneous transverse members or the use of links for connecting the back when in extended position with the uprights of the bench.

20 Still further objects of the invention are to provide metallic operating members readily attachable to the respective parts of the 25 bench of the class described to allow the manipulation of the back of said bench from its normal inclined position into an extended horizontal position to serve as a table and which operating members are inconspicuous so as not to detract from the appearance of the article.

Additional objects of the invention are to 30 generally improve upon and simplify the construction of the furniture of the class described and to provide simple means for interlocking the adjoining edges of the horizontally extending portions of two adjacent benches.

35 Other objects of the invention are to form the supporting understructure collapsible so that it may be folded against the underside of the seat thereby enabling the shipment or storage of the bench of my improved construction, in a knock down and compact condition.

40 With these and other objects in view, my invention consists of certain novel features of construction and arrangements of parts hereinafter more fully described, claimed and 45 illustrated, in which—

Figure 1 is an end elevational view of a pair of benches of my improved construction and arranged in cooperative relation with the backs extended into horizontal table positions.

55

Figure 2 is a top plan view of same.

Figure 3 is a rear elevational view of a single bench with the back thereof extended into a horizontal position.

Figure 4 is an enlarged end elevational view of a bench of my improved construction with the back thereof arranged in a normal position.

60

Figure 5 is a fragmental rear elevational view of the bench with the back thereof occupying a normal position.

65

Figure 6 is a fragmental transverse cross section through the bench showing the back thereof in a horizontal position.

Figure 7 is a vertical cross section taken on line 7—7 of Figure 6.

70

Figure 8 is a vertical cross section taken on line 8—8 of Figure 6.

Figure 9 is a fragmental cross section taken on line 9—9 of Figure 2.

75

Figure 10 is a bottom view of one of the interlocking members utilized for interlocking the adjoining edges of two back sections when extended into horizontal positions.

Figure 11 is an end elevational view of a modified form of my improved bench and showing the latter in extended position for use as a combined table and bench.

80

Figure 12 is an end elevational view showing said modified form in folded or knock down position.

85

Figure 13 is a rear elevational view showing said modified form in extended position.

Figure 14 is a top plan view of same but showing the back occupying the normal position.

90

Figure 15 is an enlarged plan view with the cover or back section in cross section and showing the understructure or supporting framework folded against underside of the seat section.

95

Figure 16 is a vertical section taken on line 16—16 of Figure 15.

Figure 17 is an enlarged detail view taken on line 17—17 of Figure 14.

100

Figure 18 is a detail view taken on line 18—18 of Figure 17.

Figure 19 is an enlarged view taken on line 19—19 of Figure 14.

5 Figure 20 is an enlarged view taken on line 20—20 of Figure 18.

Referring by numerals to the accompanying drawings, 10 indicates the seat section of a bench, and 11 indicates end frames for supporting said seat. These end frames comprise legs 12, horizontal top rails 14, and intermediate rails 15. The end frames are connected together by a front rail arranged adjacent to the seat 10 and a horizontal rail 17 extending between intermediate rails 15. Extending upwardly from end frames 11 are uprights 18, which are preferably inclined rearwardly to provide the proper inclination for a back 19 which is carried thereby.

20 This back 19 which in the present instance consists of a pair of longitudinal boards, has secured thereto near each end a transverse member 21 which is preferably formed of angle iron and is arranged adjacent to the 25 inner side of the corresponding upright 18. The projecting flange 22 of each angle iron 21 is provided with a longitudinally disposed slot 24 for the reception of a bolt 25 which is non-rotatably seated in an aperture 26 30 formed in upright 18 near the upper end thereof and extends inwardly and transversely therefrom. The threaded projecting end of bolt 25 receives a winged nut 27 which can be tightened on said bolt so as to 35 clamp flange 22 against upright 18 and thus secure back 19 in position on said uprights. The extreme end of bolt 25 receives suitable locking means such as a cotter pin 28 which prevents the complete disengagement of the 40 winged nut 27 from bolt 25 thereby avoiding the accidental displacement and loss of said nut.

Flange 22 is of sufficient depth to allow the spacing of slot 24 a suitable distance from 45 back 19 and bolt 25 is spaced a suitable distance from the inner edge 18a of uprights 18, so that when back 19 occupies its normal position, it rests snugly against edges 18a. When in this normal position, the upper ends 50 of slots 24 engage bolts 25 and the lower edge 19a of back 19 rests rearwardly of and against rear edges 10a of seat 10. In this manner, the back 19 is held, both at top and bottom, in close contact with edges 18a and 55 is locked against accidental lateral movement.

When it is desired to convert the bench into a combination bench and table, winged nuts 27 are loosened and the back 19 is then slid upwardly and is then swung into a horizontal position with bolts 25 as the pivots. The upper end of each upright 18 is finished with a flat horizontally disposed surface for receiving the underside of back 19 so as to 60 form a support for said back when the latter 65 is moved into a horizontal position.

In order to protect the upper ends of uprights 18 against injury and provide smooth operating surfaces and enable accurate positioning of the back with respect to said uprights, a metallic lining member 29 is provided for the upper end of each upright. This member 29 is preferably in the form 70 of a right angle plate 30 having a horizontally disposed flange 31 adapted to be placed on top of the horizontal face of said upright and having a depending portion or flange 32 which fits against the inner face of upright 18 and contacts with the corresponding face of flange 22. This depending flange 32 is provided with an aperture 34 for receiving bolt 25 and is further provided with an aperture 35 for receiving the counter-sunk head of a wood screw 36 which latter secures member 30 in position on the upright. Members 30, being formed of metal, can be manufactured 75 accurately and can be used as guides or templets in properly locating bolts 25 on the uprights. As the depending flange 32 is disposed on the inner side of each upright 18 it is not visible and does not effect the appearance of the bench. At the same time, it reduces friction between the flange 22 and upright 18 and insures accurate positioning 80 of the back as it eliminates close fit between flange 22 and uprights 18.

In order to provide for the interlocking of the adjoining edges of backs 19 when the latter occupy extended positions, the upper edge 19b of each back 19 is provided at a 90 point equi-distant from flanges 22 with a plate member 37 secured to back 19 by suitable fastening devices 38 and having its other edge terminating in a rearwardly and downwardly presented hook 39 which extends a suitable distance beyond the edge 19b. A 100 slot 40 is formed in plate 36 parallel with hook 39 and is adapted to receive the hook of member 37 of the adjacent back as shown in Figure 9. Each edge 19b is undercut to form a recess 41 adjacent to slot 40 so as to permit insertion of hook 39 of the adjoining edge into said slot. The interlocking members 37 are formed so that they are interchangeable and adapted to interlock with each other. In addition to this interlocking feature, hook 110 portions 39 may be used as a handle in moving the back 19 from its normal position into extended table position. As the member 37 is placed equi-distant from flanges 22, the pull exerted at this central point will maintain flanges 22 in parallelism with the side portions of uprights 18 thereby preventing binding and sticking of the back and facilitating the positioning thereof.

The form disclosed in Figures 1—10 inclusive, shows my invention applied to the bench preferably made of wood and having non-collapsible supporting frame work or under-structure. In Figures 11—20 a form is disclosed showing the bench made collapsible 120

so that it may be folded into a compact form when not in use.

In this form, the seat 44 is formed box-shaped having downwardly presented marginal flanges 45 which provide a box-shaped recess 46. The back section 47 is operatively mounted on seat 44 by means of arms 48. This back section 47 is designed to serve as a cover for box 46 when the bench occupies collapsed position. The supporting framework 49 is movably mounted on the underside of seat 44 and is foldable within recess 46 and is entirely enclosed when back section 47 is placed over the recessed side of section 44.

This supporting framework comprises a pair of end frames 50 and a strut member 51 which latter is pivotally mounted intermediate its ends by means of a bracket 52 fixed to the underside of seat 44.

Each end frame 50 consists of a front leg 53 pivotally mounted at its upper end, as indicated at 54, in order to permit the folding thereof rearwardly against the underside of seat 44. The lower end of each leg is provided with an enlargement 53a and receives the corresponding end 51a of strut 51 which latter extends obliquely from bracket 52 toward the lower end of each leg 53.

A tubular section 55 is loosely disposed on each leg 53 and its ends terminate adjacent to pivotal mounting 54 and strut end 51. The rear leg 56 of each end frame 49 is preferably formed tubular and is bent to provide a horizontally disposed portion 56a, a rearwardly and downwardly extending portion 56b terminating in a foot 56c and a front end 56d. This latter is inclined downwardly and forwardly and is secured to tubular member 55 near the upper end thereof. Thus said tubular member forms a pivotal mounting for member 56 so that the latter can be swung in a horizontal plane from its rearward or transverse position inwardly and forwardly into a longitudinal position whereupon each end frame 50 may be folded against the underside of seat 44 by swinging the front legs 53 rearwardly on pivotal mountings 54.

This pivotal connection 54 is preferably formed on the front end of a bar 57 which is disposed transversely of seat 44 and screwed to the underside thereof near each end of same by suitable fastening means such as rivets 58.

The forward end of each bar 57 is rebent to present the extremity 57a thereof rearwardly in spaced relation with pivotal mounting 54. A semi-circular notch 59 is formed in end 57a and forms a seat for the upper end of tubular member 55 when the front leg 53 occupies vertical position. In this manner the front legs 53 are engaged by a rigid portion associated with the seat at a point spaced from pivot 54 thereby reinforcing said leg and rendering it more steady. The rear end of bar 57 is bent to

bring the extremity 57b thereof substantially at right angles to the oblique portion 56b, said end 57b being provided with a semi-circular notch 60 for engaging said oblique portion. By disposing portion 57a at right angles to the leg portion at its point of engagement therewith, the danger of said end 57b to bend or be distorted when placed under pressure is thereby reduced to a minimum. The transverse bars 57 in addition to providing notched seats or bearings for the leg portions and means for pivotally mounting the front leg 53 also serve to reinforce the seat section 44 so that the latter can be made of comparatively light sheet metal. The intermediate portion of each bar 57 also serves as a bearing for the intermediate portion 56a of the rear leg when the latter occupies extended rearward position.

Arms 48 which form means for positioning and supporting section 47 relatively to section 44 are pivotally mounted near their lower ends to the end flanges 45a by means of pins or screws 61 which are secured to said end flange or said end walls 45a and project laterally therefrom. The lower end of each arm 48 is provided with a longitudinally disposed slot 62 for receiving pin 61. Each pin 61 is disposed near the lower edge of flange 45a so as to space it as far as possible from a projection 63 which extends laterally from each wall 45a and is spaced rearwardly and upwardly from pin 61. This projection 63 is designed to engage the rear edge of arm 48 when the latter occupies extended position and serves to support the latter in conjunction with pin 61 at the appropriate angle suitable for properly positioning section 47 when the latter is used as a back for the bench. The free or outer end of each arm 48 is operatively engaged with the end flange 47a of section 47 by means of a pin or a screw 64 secured to said end of arm 48 and passing through the slot 65 longitudinally disposed in each end flange 47a. These end flanges are disposed adjacent to the outer sides of arms 48 so that the said arms bear against the underside of said section 47.

By means of the slot and pin connection between arms 48 and section 47 the latter can be adjusted relatively to said arms either into a horizontal position as shown in full lines in Figure 11 or into an inclined back position as shown in dotted lines in said figure. The outer or free end of each arm 48 is provided with an extension 66 disposed angularly to said arm and occupying horizontal position when arm 48 occupies inclined extended position. These extensions 66 bear against the underside of section 47 when the latter occupies horizontal or table position and serve in conjunction with pins 64 to support said section 47 in said horizontal extended position.

When it is desired to use section 47 as a

back for the bench, said section is moved forwardly and then downwardly until the opposite ends of slot 65 engage pins 64 and the underside of said section 47 rests against the forward edges of arms 48. When in this position the lower edge of section 47 is disposed behind a shoulder or projection 44a which latter is presented upwardly from seat 44 and holds the lower edge of section 47 in position against arms 48.

When the supporting framework 50 is folded in recess 46 as shown in Figure 15, section 47 is brought against the recessed side of section 44 to close the same. To this end the lower ends of arms 48 are slotted as indicated at 62 in order to bring the said arms into horizontal position and allow the section 47 to pass the forward edge of section 44 whereupon said section 47 can be slid over the recessed side of said section 44 as shown in Figure 12. In folding the bench, section 44 is placed on the ground in an inverted position with the recess 46 presented upwardly in order to facilitate the operation. A box 67 may be placed in recess 46 as shown in Figure 15 and said box can be preferably held in position by suitable spring clips 68. This box or container can be used either as a foot stool or for other purposes. The collapsible bench, when in collapsed position, occupies very little space so that it can be easily handled, thereby facilitating shipping and storage thereof and is particularly adapted to be carried in automobiles for outings and the like.

The particular mounting of the back section permits the latter to be moved from the normal position into an extended table position without the necessity of detaching said back section or the mounting thereof. My convertible bench is of simple but durable construction and can be adjusted with ease by an inexperienced person.

While I have disclosed the preferred form of my invention, it is obvious that various changes can be made in the construction of my bench without departing from the spirit of my invention.

I claim:

1. A bench of the class described comprising in combination a supporting frame provided with a seat and having a pair of fixed upright end members the upper end of which terminates in rearwardly and horizontally disposed extensions, said uprights being spaced a suitable distance from each other, a back normally disposed against the forward edges of said uprights with the lower edge of said back disposed rearwardly of the rear edge of said seat, transversely angle members fixed to the underside of said back in juxtaposed relation with said uprights, a horizontally disposed pin carried by the upper end of each upright in spaced relation with the extension thereof, each pin having

pivotal and sliding interengagement with the corresponding transverse member whereby said back can be moved around the axes of said pins into an extended horizontal position with the underside of said back resting on the upper edges of said rearwardly and horizontally disposed extensions of said uprights, and means on said pins for locking said back in position.

2. A convertible bench comprising in combination a supporting frame provided with a seat having a pair of fixed upright end members, the upper ends of which terminate in rearwardly and horizontally disposed extensions, a back normally disposed against the forward edges of said uprights with its lower edge arranged rearwardly of the rear edge of said seat, a transverse member secured to the underside of said back near each end thereof and provided with a laterally projecting slotted portion arranged in juxtaposed relation with one side of the corresponding upright, a horizontally disposed pin seated in the upper end of each upright and engaging the slot of the corresponding transverse member thereby enabling said back to be moved pivotally and slidably relative to said uprights from its normal inclined position into a horizontal rearwardly extended position to form a table with the underside of said back resting on the upper edges of said extensions, and fastening devices screw seated on the threaded ends of said pins for clamping the slotted portions of said transverse members against said uprights to lock said back in position.

3. A convertible bench comprising in combination a supporting frame provided with a seat and having a pair of upright end members terminating at their upper ends in horizontally and rearwardly disposed extensions, a back normally disposed against the forward edges of said uprights with its lower edge arranged rearwardly of the rear edge of said seat, transverse angle members secured to the underside of said back and having the vertically disposed flanges slotted longitudinally and arranged in juxtaposed relation with said uprights, a horizontally disposed pin seated in the upper end of each upright and engaging the slot of the corresponding transverse angle member thereby enabling said back to be moved pivotally and slidably relative to said uprights from its normal inclined position into a horizontal extended position to form a table with the underside of said back resting on the upper edges of said horizontally and rearwardly disposed extensions of said uprights, fastening devices screw seated on the threaded ends of said pins for clamping the slotted portions of said transverse members against said uprights to lock said back in position, and means for engaging said fastening devices to prevent the displacement thereof from said pins.

4. A convertible bench comprising in combination a supporting frame having a seat and a pair of upright end members extending upwardly therefrom and terminating in horizontally and rearwardly disposed extensions, a horizontally disposed pin seated in each end of said upright in predetermined spaced relation with said horizontally disposed extensions and the front edges of said uprights, a back normally resting against the forward edges of said uprights and extending rearwardly of said seat, an angle iron transversely fixed to the underside of said back near each end thereof in juxtaposed relation with each upright and having its projecting flange slotted longitudinally for receiving the corresponding pin whereby said back can be moved slidably and pivotally around the axis of said pins. 70
- 10 5. A convertible bench comprising in combination a supporting frame provided with a seat and having a pair of upright end members projecting upwardly and having their upper ends terminating in rearwardly and horizontally disposed extensions, and means on each pin for clamping the slotted flange against the adjacent upright. 75
- 15 6. In a convertible bench the combination of a supporting frame provided with a pair of uprights having their upper ends formed with rearward horizontal extensions, a back adjustable about said upright members from its normal inclined position into a horizontal table position, a metallic lining member angular in vertical cross section and attachable to each extension and having the horizontally disposed flange resting on the upper edge of the extension and having the vertically disposed flange attachable to one side of each upright, a pin seated in said vertical wall and extending transversely through said upright, an angle iron attached transversely to the underside of the back near each end thereof in juxtaposed relation with said uprights and provided in its projecting flange with a longitudinally disposed slot for receiving the projecting pin whereby said back can be adjusted slidably and pivotally about said pins, 80
- 20 and means on each pin for engaging the projecting flange of the corresponding angle iron and securing said back in position. 85
- 25 7. In a convertible bench the combination of a supporting frame provided with a pair of uprights having their upper ends formed with rearward horizontal extensions, a back adjustable about said upright members from its normal inclined position into a horizontal table position, a metallic lining member angular in vertical cross section and attachable to each extension and having the horizontally disposed flange resting on the upper edge of the extension and having the vertically disposed flange attachable to one side of each upright, a pin seated in said vertical wall and extending transversely through said upright, an angle iron attached transversely to the underside of the back near each end thereof in juxtaposed relation with said uprights and provided in its projecting flange with a longitudinally disposed slot for receiving the projecting pin whereby said back can be adjusted slidably and pivotally about said pins, and a winged nut on the projecting end of each pin for engaging the projecting flange of the corresponding angle iron and securing 90
- 30 said back in position. 95
- 35 8. In a convertible bench the combination of a supporting frame provided with a pair of uprights having their upper ends formed with rearward horizontal extensions, a back adjustable about said upright members from its normal inclined position into a horizontal table position, a metallic lining member angular in vertical cross section and attachable to each extension and having the horizontally disposed flange resting on the upper edge of the extension and having the vertically disposed flange attachable to one side of each upright, a pin seated in said vertical wall and extending transversely through said upright, an angle iron attached transversely to the underside of the back near each end thereof in juxtaposed relation with said uprights and provided in its projecting flange with a longitudinally disposed slot for receiving the projecting pin whereby said back can be adjusted slidably and pivotally about said pins, and a winged nut on the projecting end of each pin for engaging the projecting flange of the corresponding angle iron and securing 100
- 40 said back in position. 105
- 45 9. In a convertible bench the combination of a supporting frame provided with a pair of uprights having their upper ends formed with rearward horizontal extensions, a back adjustable about said upright members from its normal inclined position into a horizontal table position, a metallic lining member angular in vertical cross section and attachable to each extension and having the horizontally disposed flange resting on the upper edge of the extension and having the vertically disposed flange attachable to one side of each upright, a pin seated in said vertical wall and extending transversely through said upright, an angle iron attached transversely to the underside of the back near each end thereof in juxtaposed relation with said uprights and provided in its projecting flange with a longitudinally disposed slot for receiving the projecting pin whereby said back can be adjusted slidably and pivotally about said pins, and a winged nut on the projecting end of each pin for engaging the projecting flange of the corresponding angle iron and securing 110
- 50 said back in position. 115
- 55 10. In a convertible bench the combination of a supporting frame provided with a pair of uprights having their upper ends formed with rearward horizontal extensions, a back adjustable about said upright members from its normal inclined position into a horizontal table position, a metallic lining member angular in vertical cross section and attachable to each extension and having the horizontally disposed flange resting on the upper edge of the extension and having the vertically disposed flange attachable to one side of each upright, a pin seated in said vertical wall and extending transversely through said upright, an angle iron attached transversely to the underside of the back near each end thereof in juxtaposed relation with said uprights and provided in its projecting flange with a longitudinally disposed slot for receiving the projecting pin whereby said back can be adjusted slidably and pivotally about said pins, and a winged nut on the projecting end of each pin for engaging the projecting flange of the corresponding angle iron and securing 120
- 60 said back in position. 125
- 65 11. In a convertible bench the combination of a supporting frame provided with a pair of uprights having their upper ends formed with rearward horizontal extensions, a back adjustable about said upright members from its normal inclined position into a horizontal table position, a metallic lining member angular in vertical cross section and attachable to each extension and having the horizontally disposed flange resting on the upper edge of the extension and having the vertically disposed flange attachable to one side of each upright, a pin seated in said vertical wall and extending transversely through said upright, an angle iron attached transversely to the underside of the back near each end thereof in juxtaposed relation with said uprights and provided in its projecting flange with a longitudinally disposed slot for receiving the projecting pin whereby said back can be adjusted slidably and pivotally about said pins, and a winged nut on the projecting end of each pin for engaging the projecting flange of the corresponding angle iron and securing 130
